UNITED STATES PATENT OFFICE.

GEORGE RABOLD, SR., OF MCKEESPORT, PENNSYLVANIA, ASSIGNOR TO NATIONAL TUBE COMPANY, OF PITTSBURGH, PENNSYLVANIA, A CORPORATION OF NEW JERSEY.

MANUFACTURE OF SEAMLESS TUBES.

1,412,196.

Specification of Letters Patent. Patented Apr. 11, 1922.

Application filed March 26, 1921. Serial No. 455,844.

To all whom it may concern:

Be it known that I, GEORGE RABOLD, Sr., a citizen of the United States, and resident of McKeesport, in the county of Allegheny and State of Pennsylvania, have invented certain new and useful Improvements in the Manufacture of Seamless Tubes, of which the following is a specification.

This invention relates to a method of making seamless tubes, and more particularly to a method of making seamless tubes having an internally upset end, and has for its principal object the provision of a method whereby an internally upset end may be formed in a tube during the drawing process used to reduce the wall thickness of the tube.

Another and important object is the provision of a method whereby the end of a seamless tube may be internally upset for any desired length during the drawing operation.

The several successive steps of my process or method are illustrated in the accompanying drawings, in which:

Figure 1 is a plan view of a square section of rolled plate or blank from which the tube is to be formed.

Figure 2 is a plan view of the plate or blank after it has been cut to circular form.

Figures 3 and 4 are sectional elevations of the plate or blank after it has passed through successive cupping operations.

Figures 5 to 9, inclusive, are sectional elevations of the blank after it has been drawn over successively smaller mandrels having reduced forward ends to form an internally upset portion.

Figure 10 is a sectional elevation of the completed tube showing the closed end cut off.

In the operation of my improved method, a suitable rolled plate or blank 2 is cut cylindrical and then heated until it becomes sufficiently ductile to be cupped. The heated plate 2 is then forced through a suitable cupping die forming a cupped blank 3, as shown in Figure 3. The cupped blank 3 is then reheated and forced through a smaller cupping die forming an elongated cylindrical cupped blank 4 of sufficient size to be drawn over a mandrel.

After the cylindrically shaped cupped blank 4 has been formed, it is reheated to a drawing temperature and placed on the

mandrel 5 having a reduced forward end 6, and the blank is drawn over the mandrel by forcing it through a series of dies 7. This drawing operation will force the metal, at the forward or closed end 8 of the blank, inwardly around the reduced end 6 of the mandrel 5, forming an internally upset portion 9, and since the metal of the blank yields inwardly around the reduced portion of the mandrel the dies 7 will draw less metal from the walls of the blank over the upset portion than from the remaining portions, thus forming a cylindrical blank having an internally upset portion 9 of greater wall thickness adjacent its closed end.

The blank 4 is then reheated and drawn over successively smaller mandrels 5 having reduced inner ends 6, until the desired gage and diameter are secured, the internally upset portion 9 being maintained throughout the successive steps.

After the blank is drawn to the desired gage and diameter the closed end 8 is cut off by any suitable means, such as a lathe, and a finished open tube X is formed having the internally upset portion 9.

It will be understood that while I have shown two cupping steps and five drawing steps I do not wish to be limited to such number of steps since they may be varied according to the size and character of tube being formed.

I claim:

1. The method of making tubes having an internally upset end, which consists in forming a cupped blank, reducing the blank to gage and diameter in subsequent drawing steps, and upsetting the blank internally adjacent its cupped end in one of the drawing steps and maintaining said upset end during the subsequent drawing steps.

2. The method of making tubes having an internally upset end, which consists in forming a cupped blank, drawing said blank through suitable dies over a mandrel to reduce its gage and diameter and to internally upset said blank adjacent its closed end, reducing said blank to finished gage and diameter by a plurality of subsequent drawing operations, and maintaining said upset end during the subsequent drawing operations.

3. The method of making tubes having an internally upset end, which consists in forming a cupped blank, drawing said

- blank through suitable dies over a mandrel to reduce its gage and diameter and to internally upset said blank adjacent its closed end, reducing said blank to finished gage and diameter by a plurality of subsequent drawing operations, maintaining said upset end during the subsequent drawing operations, and cutting off the closed end of the blank to form an open tube.
- 10 4. The method of making tubes having an internally upset end, which consists in forming a cupped blank, drawing said blank through suitable dies over a mandrel of reduced diameter toward its inner end to reduce the gage and diameter of and internally upset said blank, reducing said blank to finished gage and diameter by a plurality of subsequent drawing operations, in which said blank is drawn through successively smaller dies and over successively smaller mandrels, and maintaining said internally upset portion of the blank during said subsequent drawing operations.
- 15 5. The method of making tubes having an internally upset end, which consists in forming a cupped blank, drawing said blank through suitable dies over a mandrel hav-
- ing its inner end reduced forming a shoulder thereby reducing the gage and diameter of said blank and forming an internally upset portion of greater wall thickness adjacent its closed end, reducing said blank to finished gage and diameter by a plurality of subsequent drawing operations, in which said blank is drawn over successively smaller mandrels having correspondingly reduced inner ends, thereby maintaining said internally upset portion during said subsequent drawing operations, and removing the closed end of said blank to form a finished tube.
- 20 6. The method of making tubes having an internally upset portion, which consists in forming a cupped blank, and drawing said blank over a mandrel having a portion of its length of reduced diameter, thereby reducing the gage and diameter of said blank and forming an internally upset portion corresponding to the reduced portion of said mandrel.
- 25 In testimony whereof, I have hereunto signed my name.

GEORGE RABOLD, Sr.
